CLAIM

The ornamental design of a combined table and floor lamp, as shown and described.

DESCRIPTION

FIG. 1 is a front perspective view of a combined table and floor lamp showing my new design; and
FIG. 2 is a side perspective view thereof on an enlarged scale.

The shade is moveable and is shown turned toward the front in FIG. 1 and toward the side in FIG. 2.
